ATTORNEY

UNITED STATES PATENT OFFICE.

CURTIS A. SMITH, OF ELGIN, ILLINOIS, ASSIGNOR TO ROBERT CARL, OF SAME PLACE.

SELF-ADJUSTING WATCH-KEY.

SPECIFICATION forming part of Letters Patent No. 279,196, dated June 12, 1883.

Application filed April 23, 1883. (No model.)

To all whom it may concern:

Be it known that I, CURTIS A. SMITH, a citizen of the United States of America, residing at Elgin, in the county of Kane and State of Illinois, have invented certain new and useful Improvements in Self-Adjusting Watch-Keys, of which the following is a specification, reference being had therein to the accompanying drawings.

10 This invention relates to improvements in that class of watch-keys arranged to fit different sizes of winding-arbors in watches and to be self-adjusting; and it consists of the novel devices and combinations of devices hereinabove described and specifically claimed.

15 In the drawings, Figure 1 represents a side elevation of my improved watch-key; Fig. 2, a longitudinal section of the same; Fig. 3, an elevation of the jaws detached; Figs. 4 and 5, 20 elevations of the watch-key, its exterior case being removed; Fig. 6, the coupling device of the two sections of the clamp and spring-tube developed; and Fig. 7 is an end view of the watch-key.

25 Corresponding letters in the several figures of the drawings designate like parts.

A denotes the case, which is a true cylindrical tube, having a partially-fluted surface for a finger-hold. Into this case A is snugly fitted a cylindrical tube, composed of two sections, B and B', which are coupled or halved together by a hook-joint, a, so as to enable their being readily taken apart and put together again, and when thus put together to form a rigid connection. The section B of this tube is closed at its extremity b, and the section B' is contracted at its end c to bear upon the projecting conical portion of the jaws C C', that form the forceps or watch-key point.

30 These jaws C C' have each a V-groove, that from opposite sides snugly fit and grasp the squared winding-arbor, and are formed in one piece with the cylindrical shank D, and with an intermediate circular spring, d, that tends 35 to open the jaws and yields to contracting the same. The shank D of jaws C C' is snugly fitted into tube B', and is secured to the case A by a pin, e, passed through a hole in shank D and case A, and through longitudinal slots f

40 in tube-section B' in a manner that jaws C C'

are held rigid with case A, and that tube B B' is allowed a longitudinal sliding movement. A spiral spring, E, inserted into tube B, between its closed end b and the end of shank D, tends to push such tube in the direction for 55 its closed end to extend out of the top of the case, and that its contracted end c will draw the cone-shaped jaws C C' together.

For applying the watch-key, I hold its case between the fore and middle finger, and then 60 by pressing with the thumb upon the projecting closed end of tube B the jaws C C' will be released and will be opened by their spring d, and now by placing the jaws over the winding-arbor and then releasing tube B the jaws will 65 be tightened upon the winding-arbor by the action of spring E, and will retain their hold during the winding operation and until released by depressing the head of tube B again.

For putting this watch-key together, I first 70 insert the jaws C C' with their shank D into tube-section B', and the spring E into tube-section B, and then I lock the hook-joints of the two sections B B' together. Next I slide the case A over the tube B B' and insert the 75 pin e into the holes of shank D and case A, when the key is ready for use.

This watch-key is applied to or detached from the winding-arbor of a watch with great ease and without causing an end pressure to 80 such arbor. It is self-holding to the arbor during the operation of winding up the watch, and while not used its jaws are closed, so as not to be clogged between their joints by dust or other matter, as is the case with self-adjusting watch-keys that have open jaws to be closed only for grasping the arbor.

The device in its construction and arrangement is simple and convenient, and is not liable to be broken or get out of order.

90 This watch-key has the advantage that for grasping larger winding-arbors of heavy watches the jaws project less from out the contracted mouth of tube B', so as to be exposed to less lateral strain, and that only for grasping the smaller winding-arbors of light watches the jaws project proportionally more.

What I claim is—

1. In a self-adjusting watch-key, the conical jaws C C', connected by circular spring d with 95 100

shank D, that is secured to case A by pin e, in combination with sliding tube B, adapted to contract such jaws, substantially in the manner set forth.

5 2. In a self-adjusting watch-key, in combination with the conical jaws C C', the sliding clamp-tube B B', formed of two sections, that are detachably united by a hook-joint, a, substantially in the manner set forth.

10 3. In a self-adjusting watch-key, the case A and shank D, rigidly coupled by a pin, e, and such shank D having connected by spring d the conical jaws C C', in combination with tube B B' and spring E, the whole being construct-

ed and arranged to operate substantially as 15 set forth.

4. A self-adjusting watch-key, consisting of case A, rigidly secured by pin e with the shank D of conical jaws C C', the tube B B', connected by hook-joint a and having slots f, and spring E, all constructed and arranged substantially as described, to operate as specified. 20

In testimony whereof I affix my signature in presence of two witnesses.

CURTIS A. SMITH.
